CONVERTIBLE CHAIR FOR A CHILD

William W. Jones, Albuquerque, N. Mex., and Richard P. Niesz and Lawrence H. Sharp, Amarillo, Tex., assignors to Rocky-Hi, Inc., Amarillo, Tex., a corporation of Texas

Filed Aug. 31, 1965, Ser. No. 86,787

Term of patent 14 years

(Cl. D15—1)

FIG. 1

FIG. 2

FIG. 3

FIG. 4

FIG. 5

FIG. 6

FIG. 1 is a perspective view of a convertible chair for a child showing our design in position for use as a chair. FIG. 2 is a front view thereof in the chair position.

FIG. 3 is a top view thereof in the chair position, the bottom view thereof is substantially similar to the top view.

FIG. 4 is a side elevational view of the chair shown in an alternate position for use as a rocker.

FIG. 5 is a back view thereof in the rocker position.

FIG. 6 is a sectional view taken along line 6-6 of FIG. 2 and showing the article in position for use as a step stool.

We claim:

The ornamental design for a convertible chair for a child, as shown.
